A. Hebbard,

Pitcher,

No 18,546,

Patented Nov. 3, 1857.

UNITED STATES PATENT OFFICE.

ALONZO HEBBARD, OF NEW YORK, N. Y.

IMPROVED WATER-COOLING PITCHER.

Specification forming part of Letters Patent No. **18,546**, dated November 3, 1857.

To all whom it may concern:

Be it known that I, ALONZO HEBBARD, of the city, county, and State of New York, have invented certain new and useful Improvements in Water-Cooling Pitchers; and I do hereby declare the following to be a full description of the same.

The nature of my invention consists in the use of the combination of a woolen felt covering of an interior porcelain or glazed pitcher with the said interior porcelain or glazed ware pitcher and an external metallic shell or pitcher for the purpose of making a frigorific pitcher and at the same time of great lightness as well as non-destructibility from the action of lemonades or other acidulated articles or liquids used as cooling drinks or for other purposes; but to describe my invention more particularly I will refer to the accompanying drawings, forming a part of this specification, the same letters of reference wherever they occur referring to like parts.

Figure 1 is a vertical cut-section of the pitcher, showing by the different-colored lines the several parts.

Letter A is the shell of the pitcher, which may be made of any suitable material for such purposes, and of such size and shape as may be required. This shell is made in two parts, as shown by the dotted line b. The object of this is to facilitate the insertion of the interior pitcher in the shell.

Surrounding the earthen or porcelain pitcher C is a covering of felt D. This may be woolen cloth of one or more thicknesses, or of felt cloth of sufficient thickness to fill the entire space between the shell and porcelain pitcher, say to the thickness of one-fourth of an inch, more or less. The object of this felt covering is threefold: First, wool felts are among the best non-conducting substances known of; second, it is of less weight in pro-

portion to its non-conducting properties than any other substance for such purposes that can be found, and, third, it is elastic, and consequently affords greater protection to the exterior porcelain pitcher against fracture from external causes than could be obtained from any known material that could be used. The great desideratum in pitchers for this purpose is a tasty style combined with portability or lightness as well as frigorific properties, and to obtain these results it is believed no other combination of substances is better adapted or ever before used.

To protect the upper edges of the felt and porcelain pitcher from the action of the liquids when being poured in or out of it, a flange E is soldered to the inside of the neck of the shell, which is luted or cemented down upon and over the edges of the porcelain pitcher, and thereby securely protects it from the action of the liquids or from getting in between the shell and interior pitcher.

Letter F is the cover attached to the shell and operated by a hinge in the usual way with covered pitchers.

Having now described my invention and its mode of construction, I will proceed to set forth what I claim and desire to secure by Letters Patent of the United States.

What I claim is—

The use of the combination of the woven cloth or felt covering as an elastic non-conducting packing for a porcelain or glazed ware pitcher with the said porcelain or glazed ware interior pitcher and external metallic shell or pitcher, for the purpose of making a water-cooling pitcher, as hereinbefore set forth.

ALONZO HEBBARD.
